UNITED STATES PATENT OFFICE.

AARON B. ALLEN, OF PUEBLO, COLORADO.

CROSS-TIE AND RAIL-FASTENING.

SPECIFICATION forming part of Letters Patent No. 718,238, dated January 13, 1908.

Application filed May 1, 1902. Serial No. 105,444. (No model.)

To all whom it may concern:

Be it known that I, AARON B. ALLEN, a citizen of the United States, residing at Pueblo, in the county of Pueblo and State of Colorado, have invented certain new and useful Improvements in Cross-Ties and Rail-Fastenings; and I do hereby declare the following to be a full, clear, and exact description of the invention, such as will enable others skilled in the art to which it appertains to make and use the same.

My invention appertains to rail-fastenings or securing devices adapted to hold the rail of a railroad-track in reliable engagement with the cross-tie, the cross-tie being preferably of metallic construction and consisting of a suitably-shaped body having flanges adapted to coöperate with my attachment proper, as will be hereinafter more particularly set forth.

The object of my invention is to make it possible to securely connect the rail and the tie in such a manner that said rail may be readily disengaged from its connection with the tie for the purpose of replacement or repair.

Other objects and advantages will be hereinafter made fully apparent, reference being had to the accompanying drawings, which are to be considered a part of this application, and in which—

Figure 1 is a perspective view showing my invention complete as coöperating with the body portion of the rail. Fig. 2 is a similar view showing my securing device as coöperating with the meeting ends of the rail and illustrating a fish-plate interposed between the rail and my securing device. Fig. 3 shows a side elevation of my invention complete as illustrated in Fig. 1. Fig. 4 is a longitudinal central section of my securing device removed from its connection with the tie. Fig. 5 is an end view of the tie and a transverse section of my securing device, showing a portion of the track-rail in side elevation, while Fig. 6 is a transverse section of the rail and a longitudinal section of my securing device as illustrated in Fig. 2, showing the fish-plate coöperating with the meeting ends of the rail. Referring to the numerals upon the drawings which are employed to designate both the elements of my invention and coöperat-

ing devices, 1 indicates the tie of any preferred construction and preferably having the top portion or laterally-extending flanges 55 2, upon which the rail 3 of the track is designed to rest. In order to afford a seat for the body portion 4 of my securing device, I cut away a portion of the edge of the flange 2, as indicated by the numeral 5, in order that 60 said body portion may be seated therein. The said body portion 4 of my securing device proper is provided with the base-section 6 and upon its upper side with the terminals 7 and 8, the terminal 7 being of greater extent or length than the terminal 8 in order that my securing device may be thus adapted to coöperate directly with the track-rail or will coöperate with said rail when a fish-plate is interposed between the securing device 70 and rail. It is therefore clearly obvious that when there is no contiguous fish-plate the longer end 7 of my securing device will be disposed so that it will rest directly in engagement with the rail itself and that where 75 the meeting ends of two rails rest upon the tie and are secured together in the usual manner by the fish-plate 9 then the shorter end 8 will be disposed in direct engagement or contact with the fish-plate, whereby said rails will be 80 reliably secured in their adjusted operative positions upon the tie.

My securing device 4 is provided with two vertically-disposed apertures 10 and 11, and since the body portion 4 is provided upon 85 each side with a recess 12 I so dispose said apertures 10 and 11 that the locking-pin 13 disposed therein shall engage a semicircular recess provided in a contiguous part of the flange 2 of the tie, so that said pin will engage 90 the semicircular recess provided in the flange, and thus hold the securing device from casual displacement. When, however, it becomes desirable to remove the securing device, the pins 13 may be easily withdrawn 95 from the apertures 10 and 11, and thus permit the securing device to be moved loosely out of its seat in the flange 2.

From the foregoing description it will be seen that the simple securing device which 100 I have illustrated in the drawings is in itself adapted for engaging and holding the track-rail without regard to whether the rail itself is to be directly engaged by the securing de-

vice or whether there may be an interposed fish-plate or rail-joint. It is obvious that the securing device 4 may have only one end shaped to fit the rail or fish-plate, the other 5 end being simply rounded off, if desired. It therefore follows that my improved securing device may be cheaply and expeditiously manufactured in large quantities and that each one will be interchangeable with all of 10 the others, so that any one may be quickly and easily replaced if from any cause this should become desirable.

While the cross-tie itself may be made in any preferred form, that form of construction 15 presented in the drawings is thought to be most desirable, inasmuch as the base 14 is thus made coincident in extent with the top portion or flanges 2, thereby insuring that the cross-tie may be very securely and easily 20 embedded or disposed in its adjusted position in the road-bed.

Inasmuch as various modifications and changes may be made without departing from the spirit and scope of my invention, I desire 25 in this application to comprehend all substitutes and equivalents that may fairly fall within the purview of my invention.

Having thus fully described my invention, what I claim as new, and desire to secure by 30 Letters Patent, is—

1. The herein-described rail-securing device comprising the body portion 4 having a

base-section and a top portion said top portion comprising two oppositely-directed terminals of unequal length, said body portion 35 being further provided with pin-receiving apertures extending through said body whereby the pin will be received by a recess in a contiguous part of the tie all combined substantially as specified and for the purpose set 40 forth.

2. The herein-described rail-securing device comprising the combination of the tie having laterally-extending flanges upon its upper edge of the rail-securing device proper 45 comprising the body portion 4 having a base-section and a top portion said top portion comprising two oppositely-directed terminals of unequal length, said body portion being further provided with pin-receiving apertures 50 extending through said body whereby when said body portion is seated in a recess formed in the edge of the tie the pins extending through said apertures will engage a portion of the edge of said recess and hold said body portion in place until said pins are removed, all combined substantially as specified and for the purpose set forth.

In testimony whereof I affix my signature in presence of two witnesses.

AARON B. ALLEN.
